UNITED STATES PATENT OFFICE.

CHARLES J. CARY, OF BALTIMORE, MARYLAND.

DESIGN FOR TYPE.

SPECIFICATION forming part of Design No. 14,390, dated November 6, 1883.

Application filed May 15, 1883. Term of patent 3½ years.

To all whom it may concern:

Be it known that I, CHARLES J. CARY, a citizen of the United States, residing at Baltimore, in the State of Maryland, have invented 5 a Design for Type, of which the following is a specification, reference being had therein to the accompanying drawing.

The nature of my design is clearly shown in the accompanying typographic impression, 10 which serves as a drawing; and it consists of capitals, lower-case, figures, and points. In general, the body of the letter or character is of quadrilateral form, with angles oppositely placed in a direction from left to right, and 15 the angles are unequal. Some of the angles are obtuse and some acute. The sides of the parts which form the body may be of equal or unequal length. These general features give 20 the design the rhombic character; and I have changed the effect or appearance of any known

type-design having these general features by making the type broad face or shaded at its uppermost angle or side, and likewise shaded at its lowermost angle or side, and having hair-lines or narrow sides to connect the uppermost and lowermost parts. 25

What I claim is—

The design for printing-type herein shown and described, consisting of the bodies having quadrilateral form, with angles oppositely placed in a direction from left to right, and having a broad face at their uppermost and lowermost angle or side, and connecting hair-lines. 30

In testimony whereof I affix my signature in presence of two witnesses. 35

CHAS. J. CARY.

Witnesses:

J. EDWARD MORRIS,
JNO. T. MADDOX.
